UNITED STATES PATENT OFFICE

93,409

DESIGN FOR A CABINET FOR AIR CONDITIONING APPARATUS OR THE LIKE

Lester S. Keilholtz, Detroit, Mich., assignor to
Norge Corporation, a corporation of Michigan

Application December 13, 1933, Serial No. 50,061

Term of patent 3½ years

To all whom it may concern:

Be it known that I, LESTER S. KEILHOLTZ, a citizen of the United States and a resident of Detroit, in the county of Wayne and State of Michigan, have invented a new, original, and ornamental Design for a Cabinet for Air Conditioning Apparatus or the like, of which the following is a specification, reference being had to the accompanying drawing, constituting a part hereof:
The figure is a perspective view of my new

design for a cabinet for air conditioning apparatus or the like.

I claim:

The ornamental design for a cabinet for air conditioning apparatus or the like substantially as shown.

In testimony whereof, I have hereunto subscribed my name this 7th day of December, 1933.

LESTER S. KEILHOLTZ.
